UNITED STATES PATENT OFFICE

96,681

DESIGN FOR A HAND BAG

Isidore Lending, New Bedford, Mass., assignor to Sol Mutterperl, Inc., New York, N. Y., a corporation of New York

Application February 14, 1935, Serial No. 55,434

Term of patent 3½ years

To all whom it may concern:

Be it known that I, Isidore Lending, a citizen of the United States, residing at New Bedford, in the county of Bristol and State of Massachusetts, have invented a new, original, and ornamental Design for Handbags, of which the following is a specification, reference being had to the accompanying drawing, forming part thereof.

Figure 1 is a perspective view drawn on a slightly larger scale of a handbag in a closed position, showing my new design.

in an open position, showing one side of the handbag with the omission of surface grain.

Figure 3 is a perspective view of a handbag in an open position with the omission of surface grain as shown in Figure 1, showing the other side of the same.

The back of the handbag shown in Figure 1 is substantially the same as the front.

I claim:

The ornamental design for a handbag, as shown and described.

ISIDORE LENDING.
